UNITED STATES PATENT OFFICE.

SOLOMON E. AARON, OF BOSTON, MASSACHUSETTS.

DAVIT.

1,345,821.

Specification of Letters Patent.

Patented July 6, 1920.

Application filed March 22, 1919. Serial No. 284,474.

To all whom it may concern:

Be it known that I, SOLOMON E. AARON, a citizen of the United States, residing at Boston, in the county of Suffolk and State 5 of Massachusetts, have invented certain new and useful Improvements in Davits; and I do hereby declare the following to be a full, clear, and exact description of the invention, such as will enable others skilled in 10 the art to which it appertains to make and use the same.

This invention relates to ship handling apparatus and particularly to improvements in turning mechanism for davits.

15 One of the present methods of handling ship's lifeboats or the like consists in suspending them when being handled from a pair of davits, these commonly being in the form of bowed, tapered stanchions of considerable weight and of massive construction, which together with the weight of a loaded or unloaded lifeboat require considerable force in the operation of swinging the lifeboat from an inboard to an outboard or 25 from an outboard to an inboard position. Heretofore a common method of securing this swinging movement has been entirely through manual labor, by pressure against one or the other or both ends of the lifeboat 30 as soon as it is lifted from its chocks, and this is not only an extremely laborious but as well also a dangerous task, especially when seas are heavy. Also a system of swinging the boats in or out comprises power mechanism attached to the davits, and these are 35 operated manually or otherwise to swing the davits, and it is an especial object of the present invention to improve the power or davit turning mechanism now generally used.

40 and well known, first, so as to enable the attachment of a turning mechanism to a davit either before it is installed or after it is installed, and obviously in the latter case it is desirable and it is an object of the present invention to mount an element of the turning mechanism on the davit body in a manner to entirely eliminate the requirement of any machining or alteration of the body or construction of the body; and, furthermore, an important object of the invention 45 is to provide an element of a turning mechanism, preferably in the form of a gear, which may be readily and accurately and re-

liably connected to the body of the davit, although the latter may be of the curved or bowed type.

Again, while mechanisms have been utilized to secure mechanical power turning of davits, there are certain disadvantages in these mechanisms for the reason that the associated gear mechanisms, one of which is attached to the davit and the other to another support, tend to become dissociated or unmeshed because of the flexure or swaying of the davit, with the result that the gear 60 thereon is carried away from its driver. Again, it is not desirable to provide split gears on the davits, because this not only weakens the structure of the gear but also 65 interrupts the regularity of the tooth body, with the result that because of variation of pitch of certain of the teeth these will become jammed and possibly mutilated when moving into registration or mesh with co-operative teeth on the driver. A further 70 disadvantage of using a split gear on the davit is that the pressures and stresses developed are transmitted at one time or another to the fastening means between the 75 sections of the davit gear, and this fastening 80 means forming the weak element in the gear may be readily disrupted, with the result that the davit is rendered uncontrollable by the mechanism.

Therefore, with the above and other objects in view as will be readily manifest to those versed in the art, the invention consists in the construction, the combination, and in details and arrangements of the parts as more particularly set forth in the following specification relative to the embodiment of the invention illustrated in the accompanying drawings, in which:

Figure 1 is a view showing in section a fragment of a boat deck, and showing in elevation a pair of davits of standard type on which may be mounted and swung a lifeboat or other boat, indicated in dotted lines, this view being taken from the inboard position;

Fig. 2 is a detail sectional view along the axis of a davit, showing the improved turning mechanism and davit gear;

Fig. 3 is an elevation from the inboard side of one of the davit turning mechanisms, 105 and showing a portion of the davit; and

Fig. 4 is an elevational view from the outboard side of the davit and mechanism.

The invention is shown as adapted for use in combination with a pair of davits 2, 2, suitably stepped in the deck 3 of a vessel; these davits, as clearly shown in dotted lines, Fig. 1, being of the bowed or curved form very extensively used in this art, and no invention is claimed for the 10 construction of the davit, *per se*. The fall block, of any usual and appropriate construction and which is diagrammatically illustrated at 5, 5, Fig. 1, is attached to the head of the davit, and includes the lower 15 block suitably connected to the ends of the lifeboat, indicated by dotted lines at L.

The invention under consideration in the present case especially resides in a gear adapted to be readily mounted upon this 20 type of boat davit 2, and also resides in mechanism designed to be positively connected to the davit, so as to float therewith as the davit may flex or sway while a boat is being handled. With this in view the 25 improved davit gear is clearly shown in Fig. 2 as comprising in this instance an annulus or hub 6, of suitable axial length and which is preferably provided with a tapering bore 7, which not only facilitates the passing of 30 the annulus, on the circumference of which is formed a spiral gear 8, over the smaller and head end of the davit 2, and thence freely downward along its curved body to the substantially straight portion thereof, 35 as shown in Fig. 2, but also enables the utilization of the well known and thoroughly practical and reliable form of fastening means to secure the gear annulus in position. By thus forming the annulus with a 40 tapered body 7, the curvature of the body of the davit is compensated for through the axis of the annulus, and the gear can be quickly brought into position without necessitating the unstepping of the davit from 45 its mounting on the deck or deck structure, and furthermore enables the assembling of the parts with equal facility whether the davit has been stepped or, as suggested, is already in place. A simple, practicable, 50 and easily adjustable type of means for fastening the gear in place on the davit is shown as comprising a plurality of longitudinally adjustable wedge gibbs 9, 9, fitting respective gibbed ways 10, provided therefor in the surface of the annulus bore 7, and having at its upper ends setting and lock bolts 11, 11, which serve to jam the gibbs down firmly into their seats and inwardly upon the surface of the davit so 55 that the annulus is securely locked without requiring any machining or other alteration whatsoever upon the surface or body of the device.

The other important feature of the invention above alluded to resides in the pro-

vision of means by which a driver or actuating worm 15, keyed or otherwise secured on its shaft 16, which may be provided on its end with a crank or hand wheel 17, may be constantly held in the proper meshing 70 position with respect to the gear 8 on the davit, thus obviating accidental separation of the meshing gears owing to the swaying or flexure of the davit body with respect to its stepped bore and also with respect to 75 a suitable mounting or standard on which the driving gear 15 may be supported. To that end the gear shaft 16 is journaled upon bearings 18, formed upon or attached to a slide 19 dovetailed or otherwise slidably 80 supported on the head of a mounting or standard 20, provided with ways complementary to the base slide 19. The slide 19 is designed to shift transversely with respect to its standard 20, to follow movement of the davit 2 from any cause, and the outer end of the slide 19 is provided with a bearing, collar, or portion 21, embracing the adjacent portion of the davit 2, and as here shown is arranged just below 90 the bottom of the annulus 7. From this it will be seen that irrespective of any swaying or flexing movement of the davit 2, the gear thereon will be constantly held in mesh with the worm 15 which is secured on the 95 shaft 16, because of the fact that a driver is mounted in a sliding bearing on the slide 19, which while guided on the standard 20 permits the whole turning mechanism to shift freely with bodily oscillations of the 100 davit 2.

What I claim is:

1. The combination with a stepped davit, of a standard arranged beside the davit and wholly independent thereof, a slide mounted 105 on the standard and connected to the davit to float therewith in oscillations of the davit bodily with respect to the standard, a gear mounted on the davit, and driving mechanism mounted on said slide and engaging 110 said gear.
2. The combination with a davit and a support; of a turning mechanism slidably mounted on the support and connected to the davit so as to float therewith bodily. 115
3. The combination with a davit and a support; of a turning mechanism slidably mounted on the support and connected to the davit so as to float therewith bodily, the said mechanism including a gear and 120 its bearing slidably guided in its mounting on the support, the davit having a gear engaging the sliding gear.
4. The combination with a davit, of an integral annulus gear formed with a hub, 125 said hub having its central opening of sufficient size for placing it on the davit by sliding it over the upper end thereof, and means for fastening the gear in place.
5. The combination with a davit, of an 130

integral annulus with exterior teeth and having a tapered bore to facilitate placing the gear on the davit without necessitating un-stepping of the davit, and means for 5 fastening the gear in place.

6. The combination with a davit, of an integral annulus with exterior teeth and having a tapered bore to facilitate placing the gear on the davit without necessitating 10 un-stepping of the davit, and means for fastening the gear in place.

7. The combination with a davit, of an integral annulus with exterior teeth and having a tapered bore to facilitate placing 15 the gear on the davit without necessitating un-stepping of the davit, and means for fastening the gear in place, said means comprising tapered gibs attached to the annulus and adjustable to set the gear.

20 8. The combination with a davit, of an integral annulus with exterior teeth and having a tapered bore to facilitate placing the gear on the davit without necessitating un-stepping of the davit, and means for 25 fastening the gear in place, without requiring machining of the body of the davit.

9. A turning mechanism for upright davits, comprising a standard to be arranged adjacent to the davit but independent there- 30 of, a gear adapted to be secured on the davit and a driving gear therefor, and means slid- ably mounted on the standard for carrying the driving gear and keeping it in mesh

with the gear on the davit irrespective of 35 swaying movement of the latter with respect to the standard.

10. An integral annular gear having a tapered central opening and gib ways, wedge-gibs adapted to fit the gib ways, and means comprising bolts for locking the 40 wedge gibs in place and fastening the gear to a shaft.

11. In combination, a davit, transmission means for rotating said davit, a standard for carrying said transmission, said trans- 45 mission having a free radial movement relative to said standard.

12. In combination, a davit, a worm gear mounted thereon, a worm co-meshing with said gear, a carriage holding said worm and 50 gear in co-meshing relation, said carriage mounted to slide on its support with the swaying of the davit.

13. In combination, a davit, a gear mounted thereon, a power transmission 55 member in co-meshing relation with said gear, a bearing for holding the two said co-meshing members, in suitable co-meshing relation and means for mounting said bearing for movement in relation to the mount- 60 ing of the davit so as to slide as the davit swings.

In testimony whereof I affix my signature.

SOLOMON E. AARON.
